UNITED STATES PATENT OFFICE

ROBERT H. INGERSOLL, OF NEW YORK, N. Y.; CHARLES S. SMITH, OF LANSING, MICHIGAN, AND FREDERIC C. LEUBUSCHER, OF ESSEX FELLS, NEW JERSEY, EXECUTORS OF SAID ROBERT H. INGERSOLL, DECEASED, ASSIGNEES TO ROBT. H. INGERSOLL, INC., OF NEW YORK, N. Y., A CORPORATION OF NEW YORK

RAZOR-BLADE STROPPER

Application filed October 10, 1925. Serial No. 61,693.

This invention relates to improvements in devices for holding razor blades during stropping.

One of the objects of this invention is to provide a device of this type in which the handle and blade holder are formed integral-
5 ly in two elements which are hinged together, and are provided with members to hold the two elements in predetermined relation to each other while remaining in approximately parallel planes. The metal of the holder members is bent outward in forming, as upon a punch press or the like, as shown in Fig. 3, to form cups through which the rivet passes, while the rims of the cups are in substantial contact, as indicated at 13 in this figure, to afford a large area of contact and assure long life to the instrument. The metal of the holder members has a further outward bend 14 to form a passage 14^a transverse of the 55

10 holders when the two are brought into clamp-
ing relation. The metal of the holder members is thereafter bent inward and the two members run in substantial parallelism and 60 close together, so that they may clamp a 65
15 razor blade between themselves, one of the members, 11, for this purpose having the studs 15 formed thereon to enter the usual apertures in a double-edged blade to assure 70 the same against transverse or longitudinal 75
20 movement in the blade holders. Beyond the 80 position occupied by the razor blade the metal of the holder members has another outward bend and return, at 16, similarly adapted to 85
25 form a passage 16^a when the holder members are in the clamping position to the passage at 14^a. 90

With these and other objects in view, as will appear in the course of the following specification and claims, this invention has been illustrated in several modified forms on 30 the accompanying drawings, in which:

Fig. 1 is a plan of such a device in the closed position, with a razor blade therein ready for stropping.

Fig. 2 is a similar plan, but with the device open for the insertion or removal of a 35 razor blade.

Fig. 3 is a section on line 3—3 of Fig. 1 on an enlarged scale.

40 Figs. 4 and 5 are sections on lines 4—4 and 5—5, respectively, of Fig. 1, on the same enlarged scale.

Fig. 6 is a plan view of a modified form of the invention, in the closed position.

45 Fig. 7 is a section on line 7—7 of Fig. 6, on an enlarged scale.

Fig. 8 is a similar section to that of Fig. 7, but of a further modified form.

50 Fig. 9 is a fragmentary plan of a further modified form.

Fig. 10 is a perspective view of the guard utilized in the modified form of Fig. 9.

Fig. 11 is a section on line 11—11 of Fig. 9, on an enlarged scale.

In the form of construction shown in Figs. 55 1 to 5 the blade holders 10 and 11 are connected together by a hollow rivet 12 employed as a pivot, which permits the two holder members to swing with regard to each other while remaining in approximately parallel planes. The metal of the holder members is bent outward in forming, as upon a punch press or the like, as shown in Fig. 3, to form cups through which the rivet passes, while the rims of the cups are in substantial contact, as indicated at 13 in this figure, to afford a large area of contact and assure long life to the instrument. The metal of the holder members has a further outward bend 14 to form a passage 14^a transverse of the 60 holders when the two are brought into clamp-
ing relation. The metal of the holder members is thereafter bent inward and the two members run in substantial parallelism and 65 close together, so that they may clamp a 70 razor blade between themselves, one of the members, 11, for this purpose having the studs 15 formed thereon to enter the usual 75 apertures in a double-edged blade to assure 80 the same against transverse or longitudinal 85 movement in the blade holders. Beyond the 90 position occupied by the razor blade the metal of the holder members has another outward bend and return, at 16, similarly adapted to 95 form a passage 16^a when the holder members are in the clamping position to the passage at 14^a. 100

The holder member 10 is shorter than the member 11. The member 11 is rebent at its end 17, and folded back upon itself, to end at 18, in approximate abutting relation with the end of the holder member 10. A tubular sleeve 19 is mounted over the folded end of the member 11, and carries inwardly a pin 20 which projects into a slot 21 formed in this member 11: the slot limits the sliding movement of the sleeve 19 with regard to the members 10 and 11, but permits the sleeve to be withdrawn from embracing the member 10.

A guard is fastened permanently to the holder member 11 by means of rivets 22 and 23, as shown in Figs. 2, 3 and 4. This guard consists of the two side bars 24 and 25, which are connected integrally by the two transverse bars 26 and 27. The transverse bars 26 and 27 are formed at the position which is seated in the passages 14^a and 16^a formed by the bends 14 and 16 of the holder members, with apertures 28 (Fig. 3) for the reception of the rivets 22 and 23. The apertures are larger than the rivet shanks, and the rivets are of such dimensions that the transverse bars may rock about and slide 10 upon the rivets, and present the side bars 24 and 25 on opposite sides of the edge of the razor blade B mounted in the holder members, as shown by dotted lines in Fig. 5.

It is preferred, for strength and for compactness of construction, to arch the blade-receiving portion of the blade holders, as shown at 30 in Fig. 5.

The operation of this device is as follows: With the parts in the opened position of Fig. 2, a double-edged razor blade is placed loosely upon the studs 15, and the upper and shorter holder member 10 is swung about the pivot 12 until it lies parallel to and in close proximity to the longer member 11, the sleeve 19 having been moved to the position shown in this figure. When the end of the member 10 and the rebent end 18 of member 11 are in alinement, the sleeve 19 is forced inward over the end of the member 10 to securely 25 clamp the blade in position. While the blade is held against movement, yet the guard may rock freely for a limited distance in the passages described above, but is restricted in this movement by the sides of the holder members.

The device is now ready for use. The sleeve forms an excellent handle, and the device is drawn back and forth over a strop, reversing at each end of a stroke, by rocking 40 the blade over its edge. The strop cannot be cut during this reversal, since the side bars 22, 23 of the guard hold the blade edge away from the strop.

After stropping is finished, the sleeve 19 is pulled back, the holder member 10 swung around into the position shown in Fig. 2, and the razor blade lies free and may be easily removed for insertion in a razor frame.

During the stropping the guard rocks to 55 alternate sides of the edge of the blade, as shown in dotted lines in Fig. 5.

In the modified form of Fig. 6 the elements in general are the same as in Fig. 1, except that the holder members 30, 31 are 60 formed integrally, and are merely rebent at the handle end, as at 30^a, and a sliding clip 33 fits over the two holder members at the blade end. The same transverse passages 14^a and 16^a are provided for the reception of the 65 guard, which is again composed of the side

bars 24, 25 and the transverse bars 26, 27, and are held by rivets 22, 23. The clip 33 may be provided with a pin and slot arrangement, so that the clip cannot become detached from one of the holder members; the clip 33 for this purpose has a rivet 34 thereon (Fig. 7) which engages in the slot 35 in the member 31.

In the modified form of Fig. 8 the holder members are again of separate pieces, joined together by a transverse pivoting arrangement at the blade end. The upper member 40 has at the holder end an extension 42 which is curled around and passes through a hole 43 in the lower member 41. The guard arrangement is the same as before and is indicated by the same reference numerals. The two holder members are of the same length, and for the handle portion are substantially of the same shape. The lower member 41 has a slot 41^a of uniform width 70 therein to receive the shank of a rivet 44 which is held in a sliding block 45: this block slides in the member 41, and is guided therein by its upcurled lateral edges. The block 80 carries a further rivet 46 with an enlarged head 47 which may pass through the enlarged end 48 of a slot 49, but is prevented from passing through the slot 49 itself. In this way, by sliding the block 45 lengthwise of the holder members, the latter may be locked rigidly together. The operation of this device is the same as that of Fig. 1, except that in opening the sliding block 45 is used, and the two holder members open like the leaves 90 of a book.

The form shown in Figs. 9, 10 and 11 is substantially the same as those already described in Figs. 1 to 5 with the holder members 50, 51 having pivot 52 and passages 14^a, 16^a, but a slightly different construction is indicated for the guard, which is formed of a single piece of wire bent to form the four sides 54, 55, 56, 57 and welded or soldered together at 58. The parts of the transverse sides 55, 57, which are to enter the channels at 14, 16, are squeezed down at 59, 60 to flatten them and then perforated, as shown at 61, 62, for the reception of the rivets 63, 64. These rivets 63, 64 have the collars 65 at their bases to hold the guard in a central position in the channels at 14, 16. Any suitable type of device may be employed to hold the holder members 50, 51 in clamping position upon the blade; and the operation of 110 this device is the same as that shown in Fig. 1.

It is obvious that the invention is not restricted to the particular form or forms shown, but that any modifications may be made therein within the scope of the 115 appended claims.

I claim:

1. In a razor blade holder for use during stropping, a pair of holder members, means to hold said members permanently together 120

and permit their relative movement into blade-clamping and blade-releasing positions, means to secure said holders in blade-clamping position, bent portions formed in said members to present an open transverse passage between said members in the clamping position thereof, and a transverse bar loosely held in said passage and in permanent attachment to one of said members in the clamping position thereof, a side bar supported by said transverse bar opposite the edge of a razor blade clamped in said members, and means to hold said side bar in parallelism with the edge of the razor blade.

2. In a razor blade holder for use during stropping, a pair of holding members, means to hold said members permanently together and permit their relative movement into blade-clamping and blade-releasing positions, means to secure said holders in blade-clamping position, bent portions formed in said members to present open transverse passages between said members at each end of a razor blade clamped in said members, transverse bars in said passages and held in permanent relation to one of said members, side bars fixed to and supported by said transverse bars in parallelism to the edges of a razor blade clamped in said members, said transverse bars and the walls of said passages cooperating to limit the swinging movement of said side bars to opposite sides of the edges of the blade during the stropping operation.

3. In a razor blade holder for use during stropping, a pair of holder members held in permanent relation to each other and adapted to have relative movement into blade-clamping and blade-releasing positions, means to secure said members in blade-clamping position, bent portions in said members to form transverse passages between said members in such clamping position, and a guard formed of integral side bars located in parallelism to the edges of the razor blade clamped in said members, and transverse bars permanently attached to one of said members and located in said passages in such clamping position, said guard having a limited permissive rocking movement with regard to said members to disclose the edges of the blade at either side of the stropping operation.

In testimony whereof, I affix my signature.
ROBERT H. INGERSOLL.
